(57) **CLAIM**

The ornamental design for a laundry appliance front panel, as shown and described.

DESCRIPTION

FIG. 1 is a perspective view of a laundry appliance front panel of the present invention, the structure depicted by means of broken lines being shown for illustrative purposes only and forming no part of the claimed design.

FIG. 2 is a front elevational view thereof.

FIG. 3 is a top plan view thereof.

FIG. 4 is a right side elevational view thereof.

FIG. 5 is a left side elevational view thereof; and,

FIG. 6 is a bottom plan view thereof.
